DOUBLE POLE ELECTROMAGNETIC SWITCHING DEVICE

Wladimir de Fligué, Paris, France

Application March 18, 1955, Serial No. 495,250

6 Claims. (Cl. 200—93)

Relays or contactors having double pole double throw contacts are commonly provided and operate satisfactorily where there is sufficient power that they operate on the "all or nothing" principle, that is to say, when their coils are either fed or not fed.

Circumstances are entirely different when the current available to the coil is very low and it is necessary to close or open the two contacts simultaneously despite the fact that the energizing is progressively increasing or decreasing. Further difficulties arise when, under these conditions, breaking-power of the contacts must be available for industrial uses (for example to control the coil of a contactor), although the contacts may be misaligned as a result of accidental deformation or as a result of unequal wear thereon, and because the contacts must not rebound one from the other as they are closed.

The known double pole double throw relays, for example relays of the telephone type, comprise contact supports having resilient blades. Such relays lack sensitivity and precision because the instant at which the circuit breaks is not clearly defined because of the resiliency of the blades. Moreover, their circuit-breaking power is very low, because the contact pressure is determined substantially by the resilience of the blades.

The present invention has for its object to provide an improved double pole double throw relay or contactor which provides for substantially simultaneous closing and opening of the pairs of contacts, an appreciable contact pressure and, finally, high accuracy of operation, while ensuring that the armature is attracted and released with sudden movement, even with progressive increasing or decreasing in the exciting current.

According to this invention there is provided an armature of flat elongated form which is moved by the electromagnet against the force of a return device, the armature supporting, outside its plane, at least two movable contacts which co-act with two fixed contacts and said armature being arranged to pivot about two axes perpendicular to one another, one axis being transverse to the said armature and situated substantially in the plane of the latter and the other axis being substantially perpendicular to the plane of the armature.

Preferably the armature has its plane face in contact with a straight edge of an immovable part of the device which acts as a hinge, the armature being provided on the one hand with means to enable it to pivot in said plane face and, on the other hand, with two rigid extensions substantially perpendicular to, and to one side of, said face which extensions carry the movable contacts.

Practical applications of the invention will now be described, by way of example only, with reference to the accompanying drawings whereof:

Fig. 1 is a diagrammatic perspective view of a device according to the invention.

Figs. 2 and 3 are vertical sections showing certain details of construction of the device of Fig. 1.

Figs. 4 and 5 are plan and side views respectively of

2

a practical construction of armature according to this invention.

Fig. 6 is a perspective view of relay according to the invention incorporating the armature shown in Figs. 4 and 5.

Fig. 7 is a front view of a flexible electrical connection comprising part of the device of Fig. 6, and

Fig. 8 is perspective view of an alternating construction of member shown in Fig. 7.

10 The relay shown in Fig. 1 comprises a stirrup or U-shaped member 1 between the arms of which is the magnetic core 2 which supports the coil 3, the connections to which are indicated at 4.

15 Arranged to pivot about the straight edge 1a of the member 1 is the armature 5, the inner face of which is plane at least in the neighbourhood of the edge 1a.

Said edge and face combine to form the pivoting axis x—x.

20 The armature 5 is subjected to a return force from a permanent magnet 6, which is carried by the member 1. Alternatively this return force may be provided by a spring. The armature supports, on the same side thereof, two insulating extensions 7a and 7b which are substantially perpendicular to the plane of the armature.

25 On the ends of the extensions are the contact members 8a and 8b, which are shown as two small solid cylinders.

30 The ends of the moving-contact cylinders coact with fixed contact studs 9a, 10a in the case of the cylinder 8a and with the contact studs 9b, 10b in the case of the cylinder 8b. The contact members 8a, 8b are connected by the conductors 11a and 11b to terminals not shown, these conductors being pliable so that the armature 5 has complete freedom of movement.

35 There is secured to the electromagnet 1, 2, 3 a second permanent magnet 28 which acts on the armature 5 in opposition to the magnet 6. The provision of this permanent magnet is optional.

Let it be assumed that current is passed through the coil 3: when the attraction of the electromagnet 1, 2, 3 possibly in combination with the attraction of the magnet 28 overcomes the attraction of the magnet 6, the armature 5 pivots in the direction of the arrow F₁ and the contact members 8a, 8b both move towards the studs 9a, 9b. Since it is substantially impossible to ensure simultaneous contact of the two members 8a and 8b with the fixed studs 9a and 9b, one of them, for example 8a, will be the first to touch the stud 9a. If the armature 5 is prevented from moving lengthwise, but can pivot in its plane while remaining in engagement with the edge 1a, the bearing reaction due to contact between 8a, 9a produces a movement which tends to turn the moving armature as a whole in the direction of the arrow G, for example about the axis Y—Y that is to say, in the direction which carries contact member 8b towards the stud 9b. A very short instant after 8a and 9a have come into contact, contact will be established between 8b and 9b.

50 Because of the symmetrical arrangement of the extensions 7a and 7b in relation to the armature, if the centre about which the armature pivots in its plane is in the plane of symmetry of the armature, the contact pressure produced by attraction of the electromagnet and of the magnet 28, will be equally applied to the contact members.

55 When the exciting current in the coil 3 decreases, the attraction of the magnet 6 becomes preponderant and armature 5 pivots in the direction of the arrow F₂. According to which of the contact members (8a, 8b) is the first to come into contact with the corresponding stud (10a, 10b), the moving armature is then urged to rotate in its plane until the two contact members practically simultaneously touch the two fixed studs.

60 65 70 75 80 85 90 95 In both cases, the studs 9a, 9b on the one hand and

10a, 10b on the other hand form abutments limiting the movement of the armature 5 because of their inherent rigidity and that of the extensions 7a, 7b. It is arranged therefore that the armature when displaced in the direction of the arrow F_1 does not come into contact with the pole pieces of the electromagnet, and when displaced in the direction of the arrow F_2 it does not touch the permanent magnet 6. The danger of the moving armature "sticking" in either one of its extreme positions is thus avoided, while in addition the edge 1a may be formed simply by the contact between the faces situated at a right-angle to the arm 1b of the stirrup member 1.

As may be seen from Fig. 1, the extensions 7a and 7b are offset from the axis $x-x$ so that the movement of members 8a, 8b about the axis $x-x$ has a vertical as well as a horizontal component i. e. the movement is slightly oblique. Consequently, the moving contacts slide to a small extent across studs 9a, 9b, 10a, 10b when they move towards or away from them.

A relay according to the invention therefore comprises means for preventing translational movements of the armature in relation to an immovable part of the relay and for permitting the armature to pivot in its plane.

One construction of such means is shown in Fig. 2. Let into the face 1c of the arm 1b of the stirrup member 1 is a rod 11 which passes through a recess in the armature 5 in the longitudinal plane of symmetry thereof, the axis of the rod passing through axis $x-x$. The recess is a hemispherical socket 12 which receives a ball 13 screwed, for example, to the upper end of the rod 11 and locked thereto by a nut. This swivel joint, while allowing for the slight play necessary, permits the pivoting movement about the edge 1a, prevents translational movement of the armature in its plane and serves as a pivot for the rotation of the armature in this plane.

In order to reduce friction, this swivel joint may be constructed as shown in Fig. 3. A socket member 14 is let into the armature 5 and the rod 11 carries a cone 15, balls 16 being disposed between the cone and the socket member.

Figs. 4 and 5 illustrate a practical arrangement of armature with extensions and contacts carried thereby. Two lugs 5a and 5b of the armature 5 carry said extensions and replace the cross member diagrammatically shown in Fig. 1. Rigidly secured to the under face of the lugs are T-shaped carriers of insulating material and on each side of the carriers the blades 20 are secured by rivets 29. The carriers referred to constitute the extensions 8a and 7b of Fig. 1. An electrical connector device 30 of U-shaped form as seen in plan view (Fig. 7) or bisprial form as seen in Fig. 8 is secured to one of the carriers, together with the blades 20. The connector 30 consists of soft metal, which may be annealed to ensure that it is readily deformable. An arm 30a of connector 30 is gripped between the free ends 20a of the blades 20, while the corrugated second arm 30b constitutes a very flexible lead-in conductor equivalent to the conductors 11a, 11b of Fig. 1.

The friction of the cranked portions 29a against the portions 30a damps movement of the armature while at the same time enabling good electrical contact between the lead-in conductor and the blades 20.

The blades 20 carry the contact members 21. The contact studs consists of screws 22 (see also Fig. 6) which are received in a screwthreaded member formed by bending over a strip 23. The screw-thread is formed after the strip has been bent to the required shape, the bentover portions are held together by a rivet 24. A form of elastic nut is thus obtained which prevents inadvertent rotation of the screws 22 and which, in addition, ensures very good electrical contact. It is thus possible to obtain an accurate and lasting micrometric adjustment of the positions of the screwheads serving as contact studs.

Fig. 6 shows a complete relay according to the invention.

The electromagnet 1, 2, 3 carries the additional magnet

28 which acts on the free end of the armature 5, the provision of this magnet 28 being optional. The relay is mounted on an insulating base 25 which carries the fixed terminals 26 connecting with strip. Blades 20 are connected to the terminals 27 by the devices 30, as already described. Two other terminals may be provided on the base for the ends of the conductors 4.

In order further to reduce any spring action of the conductor carried by armature 5 the device 30 may be replaced, as illustrated in Fig. 8, by a strip 31 of tempered metal, for example silver, of sufficient length, which is coiled in the form of a double spiral. The end 31a of the strip is connected to a terminal 27 (Fig. 6), while the end 31b, which is in the form of a blade, is introduced between the ends 20 of the contact carrying blades 20.

With the arrangements described the armature is moved in one direction or the other either by the attractive force of the electromagnet or of the return permanent magnet with considerable acceleration so that a sudden movement is ensured even with small variations in the exciting current to the electromagnet. Since the armature moves rapidly if one set of contacts before the other the time interval between engagement is very small. Effectively the two sets of contacts engage simultaneously. Similar considerations apply during disengagement of the contacts. While the armature moves rapidly precautions have been taken, as described, to prevent rebound at the contacts.

The provision of a permanent magnet which acts in the same sense as the electromagnet ensures that the movement of the armature to close the contacts is further increased and also enables the armature to be held in the position to which it is moved by the electromagnet, in the absence of an energising current, without mechanical locking means. To move the armature away from such locked position it is necessary to provide manual means or auxiliary electromagnetic means.

What I claim is:

1. A double pole electromagnetic switching device comprising a magnetic core having an end with a sharp rectilinear edge, an elongated flat armature resting on said rectilinear edge and adapted to pivot both about said edge and about an axis therethrough perpendicular to said armature, two laterally extending arms fast with said armature and having end portions spaced from the plane containing said armature and on the same side thereof, a contact member on each of said portions, and two stationary contact studs cooperating with said contact members.

2. Device as claimed in claim 1 comprising a swivel joint connecting the armature to the core whereby said armature is pivotable about both the rectilinear edge and the axis therethrough perpendicular to said armature.

3. Device as claimed in claim 2 wherein the swivel joint comprises a pivot fast with the core and extending perpendicularly to the rectilinear edge, and a cup-shaped socket housed within a recess in the armature.

4. Device as claimed in claim 1 further comprising an extension of the armature beyond the rectilinear edge, a permanent magnet fast with the core and exerting attraction on said extension, and a further permanent magnet fast with said core and exerting attraction on a portion of said armature, whereby the attraction of said further magnet supplements that exerted by the core whereas the former mentioned magnet acts in opposition thereto.

5. Device as claimed in claim 1 wherein each extension comprises an insulated portion and a contact member is secured to said portion, said device further comprising a second contact member secured to the insulated portion of each extension, on opposite side thereof relatively to the first contact member and facing in opposite direction, said two contact members being electrically interconnected, two further stationary contact studs spaced from and opposite the former two studs, each contact stud

cooperating with a contact member, whereby said device is operable as a double pole double throw switch.

6. Device as claimed in claim 5 wherein the contact members on the same extension are interconnected by means of a resilient strip of tempered metal twisted to form two oppositely coiled spirals inside each other, whereby opposite and substantially equal stresses are created in said strip upon bending the same.
